UNITED STATES PATENT OFFICE.

HANS JOACHIM SPANNER, OF BERLIN, GERMANY, ASSIGNOR TO DR. ERICH F. HUTH
G. M. B. H., OF BERLIN, GERMANY.

FULL-WAVE RECTIFIER WITH GLOW CATHODE.

Application filed January 23, 1925, Serial No. 4,358, and in Germany January 25, 1924.

This invention relates to rectifiers with glow cathode which may consist of a metal filament, for instance a tungsten filament or of an electrically conducting basis which is 5 covered entirely or partly by a layer of oxide.

These cathodes were heated hitherto by a heating battery which was switched in permanently during the operation of the electron discharge tube and had consequently 10 to be of corresponding size and required to be recharged.

In this invention the cathode heating battery is rendered unnecessary during the 15 operation proper. The invention consists in heating the glow cathode during operation by the electron current which flows out of it to an anode so that the capability of the glow cathode to emit electrons is directly maintained. It is therefore no longer necessary 20 to switch the heating battery in during the time the tube is really used. The heating battery or other source of heat is switched in only for a very short time, usually for a fraction of a second, in order to cause the 25 glow cathode to glow whereupon it is switched out immediately as soon as the anode current (emission of electrons) starts. The heating battery can therefore be of very low efficiency.

30 This self-heating of the cathode by the electron emission current can, as mentioned above, be used even for ordinary filament—or plate cathodes, which are made for instance of tungsten or other convenient material.

35 The application is further favoured by using an oxide layer of alkaline earth metals or of other convenient combination and manufacture. This oxide layer offers a higher resistance against the passing of 40 the current, than uncoated electric conducting wires offer. The electron or the anode current traversing the coating layer must therefore overcome a greater resistance when traversing this coating layer and by selecting 45 the thickness of the oxide layer accordingly, it is possible to bring the glow cathode to any desired glowing temperature with the aid of the so-called Joule effect which is thus produced.

50 The use of a coating layer not only increases the emission of electrons as compared with the emission obtained by means of the commonly used metallic conducting wires but also presents still another advantage. It 55 has become known that at greater load and

consequently better utilization of a discharge vessel the anode is caused to glow by the electrons acting upon the same so that it becomes also a source of electron emission. If the anode has no coating layer favouring the 60 electron emission but only the cathode proper the quantity of the electrons emitted will preponderate on the glow cathode in comparison with the quantity of electrons issuing from the anode, even in the case that unilateral current conductivity from the cathode to the anode results owing to the preponderance of the electron emission of one of the two 65 glowing electrodes.

The glowing of the anode can be exploited in full wave rectifiers in an especially 70 economical manner. According to the invention the anode, which is concentrically disposed about the glow cathode, is subdivided into two parts by a slot, which is as 75 narrow as possible. Each part of the anode has its individual current supply. In this manner it is possible to employ one glow cathode rectifier tube as a full wave rectifier. The narrow slot is such an insignificant alteration 80 in the anode that there are for both phases the same thermic conditions when the anode is glowing. As regards the thermic conditions the similarity of the two parts of the anode can be increased by filling the 85 narrow gap between the same with a material which, although being electrically insulating, is thermically conducting.

The material must however at the temperature in question emit electrons only in a very 90 limited degree. Zirconium oxide possesses for instance all these properties. The arrangement presents the further advantage that, in contradistinction to the commonly used full wave rectifiers of the Wehnelt type 95 and others, the distance between the two anodes and the glow cathode may be considerably smaller wherefrom results a more favorable repartition of potential and a reduction of the prejudicial influence of the 100 space charge. It has thus become possible to transform in both phases even comparatively low alternating current voltages without the necessity to use artificial heating. The automatic heating of the glow cathode 105 is further favoured by the anode cylinder which tightly encloses the cathode, owing to the radiation of heat from the anodes which are brought to the glowing state, by giving corresponding dimensions to the tube. A 110

further factor which assists this is the circumstance that the closed anode arrangement absorbs heat generated by the alternating current rectified and uses the same for its own heating, this being an advantage which does not exist in the rectifiers of known type comprising two anodes arranged at a comparatively great distance the one from the other.

The improved full wave rectifier is shown 10 by way of example on the accompanying drawing wherein Fig. 1 illustrates a perspective view of one form of the anode structure of this invention; Fig. 2 illustrates a perspective view of a modified form of this invention and Fig. 3 shows a perspective view of 15 another modification of this invention. Like reference characters designate similar parts throughout the drawings.

In Fig. 1 the two cemented parts *a*, *b* of 20 the anode cylinder have the leading-in wires *c*, *d*. The glow cathode or filament *e* is stretched in the axis of the cylinder. Current is supplied to the filament *e* through the conductors *f*, *g*. The anode may also be in 25 the form of a hollow body of some shape other than cylindrical. In this invention it is essential that the anode encloses the cathode. Instead of the slot being perpendicular to the axis of the cylinder two slots disposed in the 30 direction of the axis cylinder may be pro-

vided, as shown in Fig. 2. An anode of the shape shown in Fig. 3 would also fulfill the essential requirements of the invention, only it would have a less desirable effect as regards the good and uniform repartition of 35 temperature to both anode parts.

The new arrangement can also be used with advantage for the rectification of multi-phase currents as it is only necessary to subdivide the anode by several slots into several parts. 40

By making the anode surround the glowing cathode, excessive radiation of heat from the cathode is prevented, and therefore the cathode can be more easily maintained at the proper high temperature. 45

I claim:—

1. A full wave rectifier comprising a glow cathode designed to be maintained by the discharge current at the required glowing temperature and an anode subdivided into at 50 least two parts electrically insulated the one from the other to be joined to different circuits but thermally connected the one with the other and enclosing the cathode.

2. A full wave rectifier in which the anode 55 is subdivided by slots filled with an electrically non-conducting but thermally conducting strongly electro-negative material.

In testimony whereof I affix my signature.

DR. HANS JOACHIM SPANNER.
